UNITED STATES PATENT OFFICE.

GEORGE F. FRICKE, OF CHICAGO, ILLINOIS.

DESIGN FOR A WOOD CARPET.

SPECIFICATION forming part of Design No. 20,996, dated August 18, 1891.

Application filed April 6, 1891. Serial No. 387,907. Term of patent 7 years.

To all whom it may concern:

Be it known that I, GEORGE F. FRICKE, a citizen of the United States of America, residing at Chicago, in the county of Cook and State of Illinois, have invented certain new and useful Improvements in a Design for Wood Floors, of which the following is a specification, reference being had therein to the accompanying fac-simile.

10 The accompanying fac-simile illustrates a portion of a floor ornamented with my design. The design is particularly intended to be employed in the construction of what is commonly known as "woodcarpets;" and it consists in placing the strips or pieces comprising the floors in oblong spaces. In practice the strips comprising the floor are of varying colors or light and dark, and are arranged to produce a symmetrical and pleasing effect. The strips

in one oblong space are arranged at the same 20 angle as the corresponding strips in the next oblong space, so that diamond-shaped figures are formed, while within the oblong spaces the said strips form crosses having greater length than breadth.

25 A border composed of double zigzag lines surrounds the above-described design, and the whole forms a highly pleasing and novel design for wood carpets.

30 I claim as my invention—

The design for wood carpets, substantially as shown and described.

In testimony whereof I affix my signature in presence of two witnesses.

GEORGE F. FRICKE.
